UNITED STATES PATENT OFFICE

2,316,659

APPARATUS FOR LOADING SHEATH WIRE
HEATING UNITS

John Lewis Andrews, Elmwood Park, Ill., assignor
to Edison General Electric Appliance Company, Inc., Chicago, Ill., a corporation of New York

Application July 25, 1940, Serial No. 347,446

21 Claims. (Cl. 226—23)

This invention relates to electric heating units of the sheathed type, and has for its object the provision of improved apparatus for loading heating units of this character with a suitable insulating material.

This invention has particular application to electric heating units wherein a helical resistance conductor is encased by a sheath and is embedded in and held in spaced relation with the sheath by means of an electrically insulating, heat refractory and heat conducting material, such as powdered magnesium oxide. One heating unit of this character is described in the United States patent to Charles C. Abbott No. 1,367,341, dated February 1, 1921.

This invention contemplates the provision of improved apparatus for loading the sheath of the heater with the insulating material so as to embed the resistance conductor and hold it in spaced relation with reference to the sheath, in a simple, reliable and efficient manner.

In accordance with this invention, suitable means are provided for holding the sheath in a substantially upright position, and also for holding the terminals of the resistance element, which are connected to the ends of the element, in proper relation to the sheath, generally in the vertical center line of the sheath. Suitable means is provided for feeding to the sheath the powdered magnesium oxide at a regulated rate. A suitable vibratory device is provided for imparting to the sheath intermittent impacting blows to settle the insulation within the sheath while it is being filled. A suitable centering device is arranged to be inserted in the sheath to hold the portions of the coiled resistance element between the terminals in the center line of the sheath while the sheath is being loaded. Means are provided for effecting an up and down movement of the centering device in the sheath as the insulating material is being fed to the sheath. And the centering device is constructed and arranged so that each time it is lowered it engages the top surface of the insulating material so as to displace the insulating material upwardly around the coiled resistance element in order to elevate slightly the turns of the conductor and thereby compensate for sagging of the wound resistance element due to its own weight and the weight of the settling insulating material.

The means are provided for reciprocating the centralizer including means for temporarily releasing the centralizer from the driving force when the centralizer engages the top surface of

the insulating material, and also for progressively elevating it so that the lower limit of each downward stroke of the centralizer is at a higher level in the sheath than that of the previous stroke.

Moreover, the means for feeding the insulating material to the sheath is controlled to reduce the flow of insulating material as the level of the insulating material approaches the upper end 10 of the sheath so that the density of the insulating material at the upper end of the sheath is substantially the same as that of the insulating material throughout the remainder of the sheath. Moreover, the control of the flow of insulating 15 material is such that it is stopped at precisely a predetermined high level in the sheath.

The entire apparatus is under the control of a single manually operable control lever which when operated to a predetermined position starts 20 the loading operation. Furthermore, the apparatus automatically stops itself when the loading operation has been completed.

For a more complete understanding of this invention, reference should be had to the accompanying drawings in which Fig. 1 is a fragmentary front elevation of loading apparatus arranged in accordance with this invention; Fig. 2 is a fragmentary side elevation of the apparatus of Fig. 1; Fig. 3 is a fragmentary front elevation 25 similar to Fig. 1, but illustrating certain parts of the apparatus in different operative positions than they occupy in Figs. 1 and 2; Fig. 4 is an enlarged fragmentary front elevation of the upper portion of the loading apparatus of Figs. 1—3; Fig. 5 is a fragmentary side elevation of the parts of the apparatus shown in Fig. 4, parts 30 being shown in section so as to illustrate certain details of construction; Figs. 6, 7 and 8 are sectional views taken through the lines 6—6, 7—7, 8—8 respectively of Fig. 4 and looking in the directions of the arrows associated with these lines; Fig. 9 is an enlarged fragmentary front elevation of the middle portion of the loading apparatus of Figs. 1—3; Figs. 10, 11, 12 and 35 13 are sectional views taken through the lines 10—10, 11—11, 12—12 and 13—13 respectively of Fig. 9 and looking in the directions of the arrows associated with these lines; Fig. 14 is a still 40 larger fragmentary front elevation illustrating certain parts of the loading apparatus; Figs. 15, 16, 17 and 18 are sectional views taken through the lines 15—15, 16—16, 17—17 and 18—18 respectively of Fig. 14 and looking in the direction of the arrows associated with these lines; Fig. 19 45 is an enlarged elevation in section illustrating

the sheath and resistance conductor of a sheathed heater assembled in the machine prior to the loading operation; Fig. 20 is an enlarged sectional view taken through the line 20—20 of Fig. 19 and looking in the direction of the arrows; and Fig. 21 is a fragmentary elevation, partly in section, of a finished sheathed electric heating unit of the type to which this invention is particularly applicable.

Referring to the drawings, this invention has been illustrated in one form as applied to apparatus for loading electric heating units of the sheathed type, such as described in the above-mentioned Abbott patent. A heating unit of this type has been illustrated in Fig. 21; this unit comprises a helical resistance element 10 encased by a metallic sheath 11. Suitable terminals 12 are mechanically and electrically connected to the ends of the resistance conductor 10. For this purpose, the resistance conductor is threaded on the terminals, as shown, and as fully described in United States Patent No. 1,494,938 to C. C. Abbott, dated May 30, 1924. The resistance conductor 10 is embedded in and is held in spaced relation with reference to the sheath 11 by a highly compacted mass 13 of heat refractory, heat conducting, electrically insulating material, such as powdered magnesium oxide. The powdered magnesium oxide is compressed into a dense compact mass in any suitable way as by reducing and elongating the sheath. The mass of insulating material 13 functions to hold the resistance element 10 in spaced relation with reference to the sheath, preferably so that its axis coincides with the axis of the sheath, and it also functions to conduct heat from the resistance element 10 to the sheath. The inner ends of the terminals 12 are also embedded in the powdered insulating material 13, as shown, and are insulated from the sheath 11 and held in spaced relation with it by means of the insulating material.

The apparatus for loading the sheath comprises a suitable frame-work 14 which comprises upright channel-shaped columns 15 which are arranged in spaced-apart parallel relationship, as shown in Figs. 1, 3 and 9. The columns at the bottom are provided with feet 16 which rest upon the floor or any other suitable supporting base. Secured to the upper ends of the columns 15 is a vertically positioned plate-like member 17. This plate is provided at its edges with forwardly extending sections 18 which terminate at the front in inwardly extending flanges or webs 19. The forwardly extending sections 18 are rigidly secured to the upper ends of the columns 15. For this purpose, the columns 15 are provided with extensions 20 (Figs. 1, 2, 3 and 9) which are secured to the sections 18 in any suitable manner, as by bolts 21 (Fig. 9). The flanges 19, as shown in Figs. 1, 3 and 9, terminate a considerable distance above the lower end of the plate 17. Also, it will be observed in Figs. 6, 8, 12 and 13 that the sections 18 of that part of the plate 17 below the flanges 19 are considerably shallower than are the corresponding parts of the plate that are coextensive with the flanges 19. The frame-work 14 is secured to a fixed pair of brackets 22 and 23 which may be supported by any suitable means (not shown). For this purpose, the plate 17 is rigidly secured to the bracket 22 by a screw-fastening means 24 and dowels 24a (Figs. 1, 3, 4 and 5). Interposed between the bracket 22 and the plate 17 is a spacing plate 22a. At the lower end the plate 17 is

reinforced by a relatively heavy plate 26 which is fastened to the rear surface of the plate 17 by means of rivets 26a (Figs. 9 and 10). The plates 17 and 26 are secured to the bracket 23 by the screw-fastening means 25, (Figs. 1, 3, 9 and 10).

Mounted in the lower part of the apparatus is a suitable standard 28 for supporting the heater sheath 11 (Figs. 1 and 2). The standard 28 is provided with a head 29 having in general the shape of a mushroom, and provided with an upright cylindrical extension 30 which is arranged to be inserted in the lower end of the sheath, as clearly shown in Fig. 19.

It is to be understood that the terminal 12 at the lower end of the sheath is supported in its central position with reference to the sheath by means of a suitable head 31 which is rigidly secured to the lower end of the terminal or which may be assembled on the terminal and held by means of a small head on the terminal and which is received in a recess 32 provided for it in the lower end of the sheath. This head or washer 31 in addition to holding the terminal 12 centrally of the sheath, functions to close the lower end of the sheath. The cylindrical extension 30 on the support 28 is received in the recess 32 to center and hold the lower end of the sheath against lateral displacement.

It will be further understood that before the heater sheath 11, resistance conductor 10 and terminals 12 are inserted in the loading apparatus, the resistance conductor will have been secured to the upper and lower terminals and they will have been threaded through the sheath so as to bring the head 31 on the lower terminal 12 into its recess 32.

The upper terminal 12, instead of being provided with an enlarged head like the lower terminal, is provided with a relatively small head 33. The head 33 is supported by a terminal rod 34. The terminal rod 34 at its lower end is provided with a hook 35 which is provided with a jaw 35a that engages the head and thereby retains the upper terminal 12 and the resistance conductor 10 under tension, as shown in Fig. 19. The hook is provided with an enlarged opening above the jaw, as shown, through which the enlarged head 33 may be inserted and then dropped down to engage the jaw which supports the terminal 12. The rod 34 functions to support the terminal 12 in its elevated position. The rod 34 extends on up to a point adjacent the top of the apparatus where it is secured to an arm 36. The arm 36 is supported by means of a rod 37 which extends down back of the plate 17 and is secured to a lever 38 which is pivoted to the plate 17 by means of a pin 38a (Figs. 4, 5 and 8). Mounted upon the rod 37 is a compression spring 39 which has its lower end abutting against a fixed collar 40 on the rod and its upper end abutting against a member 41 which is secured to the upper end of the member 17; as shown, the member 41 is secured to an angle member 42 which in turn is rigidly secured to the upper end of the plate 17. A suitable latch 43 controls the position of the lever 38 and holds the lever against clockwise movement, the force of which is imparted to the lever as viewed in Figs. 1, 3 and 4, by the compression spring 39. The latch 43 is provided with two seats or detents 43a and 43b to hold the lever 38 in each of two positions, in one of which it is shown in Figs. 1 and 4 and in the other of which it is shown in Fig. 3. The latch 43 is mounted upon a fixed pivot 43c (Figs.

4, 5 and 8), and it is biased in a latching direction, that is, in a counter-clockwise direction, as viewed in Fig. 4 by means of a tension spring 43d anchored to a fixed pin 43e. Attached to the lever 38 is a rod 44 whereby the lever may be moved in the counter-clockwise direction. This rod is provided with a hooked portion 44a which engages one end of lever 38 and with an eyelet portion 44b for manual operation of the lever 38.

Arranged to operate in the sheath around the resistance conductor 10 and its terminals 12 is a centralizing member 45 (Figs. 14, 15, 19 and 20). The centralizing member, as shown, is cylindrical in form and is provided with a series of vertically arranged ribs 46 on the outside spaced circumferentially about the centralizer, and which are arranged to engage the inner wall of the sheath 11, as shown in Figs. 19 and 20. It will be understood that a running clearance will be provided between these ribs and the sheath. The centralizer also has a central aperture 47 which fits about the helical coil 10. In this way the centralizer as it rises maintains the central axis of the coil substantially coincident with the axis of the sheath. The lower end of the centralizer is provided with a flat wall, and also with a second wall 41a which inclines upwardly and inwardly from the flat wall toward the central axis of the centralizer, all as clearly shown.

The centralizer 45 is threaded upon the lower end of a centralizing tube 48 which surrounds the rod 34 and extends upwardly to a point adjacent the top of the apparatus where it is secured to a transverse bridge member 49. The member 49 carries a split nut 50 which receives the tube 48 and which is rigidly clamped to it, as shown in Fig. 4. The member 49 is provided in its opposite ends with slots 51 which receive the flange-like sections 19 on the plate 17. This establishes a sliding connection between the bridge 49 and the plate 17. The bridge 49 is rigidly secured to a carriage 52, the construction of which is shown more clearly in Fig. 12. As there shown, the carriage 52 is provided with slots 53 which are received by the forward flanges of the upright columns 15 whereby the carriage may be slid up and down on these columns. A pair of parallel rods 54 function to connect the carriage 52 with the bridge 49. These rods at their upper ends are rigidly secured to the bridge by means of nuts 55, and at their lower ends are provided with laterally-extending webs or feet 56 (Figs. 9 and 12) which are rigidly secured to the carriage 52 by means of bolts 57. The carriage 52 is provided with a knob or handle 58 whereby the carriage and hence the bridge and centralizing tube 48 connected with it can be conveniently depressed by the operator, at the proper time.

Secured to the bridge 49 is a wedge cam 59 (Figs. 1, 4 and 5) which is rigidly connected to a transverse plate 60 that is substantially parallel to the bridge 49 and which is attached to the bridge by means of a pair of bolts 61. The bolts 61 are loosely arranged in the plates 49 and 60 so that these plates can be moved relative to each other for a limited distance, as determined by the length of the space between the heads of the bolts and their nuts. In Figs. 1, 4 and 5 the plates are shown at their maximum distance apart. The wedge cam 59 is arranged to be gripped by a pair of rollers 62 provided on the lower ends of lever arms 63 which are pivoted intermediate their ends to the plate 41. The upper ends of the levers 63 are biased apart by means of a compression spring 64. This spring 75

64 is mounted upon a rod 65 that is secured at its right-hand end, as viewed in Fig. 5, to a block 66 pivoted to the upper end of the right-hand lever 63, and which has its opposite end freely 5 slidably in a block 67 pivotally mounted on the upper end of the left-hand lever 63. The rod 65 carries an abutment 68 in the form of a pair of nuts threaded on the rod, as shown in Fig. 5. The compression spring 64 is interposed between the block 67 and the abutment 68 so as to bias the upper ends of the levers apart and thereby force the rollers 62 inwardly with relation to the cam 59. This cam 59 when engaged by the rollers 62 will hold the centralizing tube 48, the bridge 49 and the carriage 52 in their upper operative positions.

Also mounted on the bridge 49 is a roller 68a which when the carriage 52 is depressed by the knob 58 is moved downwardly to operate the latch 43 from its position of Figs. 1 and 4 to its 10 position of Fig. 3 under certain conditions of operation, as will be pointed out in greater detail hereinafter. The roller 68a when it is depressed 15 rides on a rail 68b which is positioned opposite a cam 43f on the latch 43 so that it positively 20 engages the cam to move the latch to its position of Fig. 3.

The upper end of the sheath 11 is rigidly secured in the apparatus in its proper position with 25 relation to the resistance conductor 10 by means of a pair of jaws 69 which are mounted upon the plates 17 and 26. The two jaws 69 are mounted upon upright shafts 70 which have their upper ends mounted in a plate 71 and rigidly secured 30 thereto by means of set screws 72.

Mounted on the lower ends of the shafts 70 are gear members 73, which as shown, are secured to their respective jaw members 69 by means of screws 74 and pins 75. The gear members 73 have intermeshing teeth 76 whereby the jaws are caused to move together on their axes. The plate 71 is roughly of T-shape and has a stem 71a extending downwardly, as shown in Figs. 15, 16, 17 and 18. Mounted within this stem 40 71a is an insert 77 and the jaws are provided with inserts 78 spaced slightly above the level of the insert 77, as shown in Fig. 15. These inserts are formed of hardened metal and cooperate to 45 function as an abutment for the upper end of the sheath 11 when the jaws are closed, as shown in Figs. 14-18. The jaws below the inserts are provided with arcuate portions 69a which when the jaws are closed fit tightly about the upper end of the sheath, as shown in Figs. 15 and 16.

50 The plate 71 is secured to the plates 17 and 26, and interposed between the plate 71 and the plate 17 is a plate 79 also roughly of T-shape, and its stem 79a is fitted behind the stem 71a of the plate 71, as shown in Figs. 15, 16, 17 and 18. The plates 71 and 79 are rigidly secured 55 to the plates 17 and 26 by screw-fastening devices 80.

The jaws 69 are provided with over-center 60 springs 81 which move them with a positive snap movement between fully opened and fully closed positions, the former being shown in dotted lines in Fig. 18 while the latter are shown in full lines in this figure. The springs 81 are of the compression type and have their opposite ends bearing 65 on collars 82 and 83 respectively. The collars 82 are provided with knife-edge seats 84 which receive knife-edge bearings 85 provided on the arms 86 attached to the jaw members, as clearly shown in Fig. 18. The opposite collars 83 are received 70 in pivot bearings 87 which are rigidly mounted

upon a supporting bracket 88 which in turn is secured to the plate 79 by means of screws 89. As shown in Figs. 15 and 18, a collar 90 is threaded on the screws 89 and is interposed between the member 79 and the supporting bracket 88, and preferably a plate 91 will be interposed between the plate 79 and the collar 90. The ends of the plate 91 function as stops for the jaw arms 86 when the jaws are in their fully opened positions, as shown in dotted lines Fig. 18. The members 86 on the jaws project through apertures 92 provided in the plates 17 and 26, as shown in Figs. 9, 14 and 18, and the springs 81 and associated mechanism are located back of these plates, as shown in Figs. 2 and 18.

A suitable hopper 93 is mounted in an elevated position upon the frame 14 in any suitable way. This hopper discharges into a chute 94. The chute 94 discharges into a member 95 which is secured to the plate 26, as shown in Fig. 15. The member 95 discharges into a passageway 96 formed in the plates 26, 17, 79 and 71, as clearly shown in Fig. 15. The passageway 96 in turn discharges into the jaws directly above the open end of the sheath 11, as clearly shown in Fig. 15. A suitable tongue-like cut-off gate 97 is placed over the mouth of the passageway 96 to control the flow of insulating material to the sheath. The cut-off 97 at its upper end is connected to a cut-off actuating lever 98 (Figs. 1, 3, 9, 14 and 15), which is pivotally mounted upon the plate 79 by means of a screw-fastening device 99. The cut-off gate 97 is secured to the lever 98 by means of a block 100 (Fig. 15) which is rigidly secured to the cut-off and which carries a pin 101 that is received in an elongated slot 102 provided for it in the lever. The pivotal movement of the lever 98 on the plate 79 is limited by a pin 103 mounted on the plates 17 and 26, as shown in Figs. 11, 14 and 15, and which is received in an arcuate slot 104 provided in the lever. The lever 98 is biased to move in a counter-clockwise direction, as viewed in Figs. 9 and 14, that is, in a direction to open the cut-off by means of a spring 105 which is secured at its lower end to the lever, as shown in Figs. 9 and 14, and at its other end is anchored to a pin 106 (Figs. 9, 11 and 12) which pin is fixed to the plates 17 and 26. The cut-off lever 98 is prevented from moving in its counterclockwise direction by means of a latch 107a which is pivotally mounted on a latch arm 107 by means of stud 107b. The latch 107a may rotate in a counter-clockwise direction with respect to the arm 107, but is prevented from turning in a clockwise direction with respect to the arm by a ledge 107c on the arm 107. A spring 107d mounted on the arm 107 normally biases the latch 107a to its position shown in Fig. 9 where it abuts the ledge 107c. The latch arm 107 is pivotally mounted on a pin 108 that is rigidly secured to the plates 17 and 26, and it is biased to move to its latching position, that is, is biased to move in the clockwise direction, as viewed in Fig. 9, by means of arm 109 (Figs. 9 and 13) which has its right-hand end, as viewed in these figures, pivotally secured to the arm 107 above the pivot 108 of the arm, and at its left-hand end forms an abutment for one end of a compression spring 110; the opposite end of this spring bears against a fixed abutment 111 so that the arm 109 and hence the arm 107 are biased to their latching positions. The abutment 111, as shown in Figs. 9 and 13, is secured to a block 112 which in turn is secured to the plates 17 and 26 by a screw fastening device 113 and dowels

113a. An opening in the block 112 serves as a guide for the left-hand rod 54.

A guide member 44c for the rod 44 is also secured at the rear of plate 26 by the screw fastening device 113.

The latch arm 107 is moved to its unlatching position to permit the lever 98 to open the feed gate 97, that is, is moved in the counter-clockwise direction, by means of a control arm 114 which is pivotally mounted upon a plate 115 which is doweled to a block 115a, a spacer 115b and the plates 17 and 26; these members are further secured by means of a screw 116. An opening in the block 115a serves as a guide for right-hand rod 54. The control arm 114 is connected to the latch arm 107 by means of a link 117 pivotally connected at one end to the lever 114, as shown in Fig. 9, and at its opposite end to the latch arm 107. When the lever 114 is depressed, that is, is moved in the clockwise direction, as viewed in Fig. 9, it moves the latch arm 107 and hence the latch 107a to release the lever 98 and thereby permit it to move in the counter-clockwise direction to open the insulating material cut-off 97. The lever 98 is returned to its latched position to shut off the flow of insulating material to the sheath by means of a cut-off cam 118 (Figs. 1, 3, 9, 14 and 15) which is mounted upon the carriage 52. This cam coacts with a roller 118a on the lever 98.

The carriage 52, the bridge 49, the rods 54 and the centering tube 48 attached to them are given a reciprocatory motion up and down with reference to the frame 14, the carriage sliding in the columns 15 and the bridge 49 sliding on the flange sections 19. This motion is imparted to these members by means of a shaft 119 (Fig. 10) which is rotatably mounted in a bearing 120 which in turn is mounted on the plates 17 and 26. The shaft 119 will be connected with any suitable constant speed drive, such as a constant speed motor (not shown) operating through a suitable gear train (not shown) interposed between the motor and the shaft. Secured to the inner end of the shaft 119 is a disc 121 which rotates in a circular recess provided for it in the bearing 120, as shown in Fig. 10. This member carries a crank pin 122 which functions to reciprocate a member 123. This member 123 is arranged to reciprocate in a path parallel to the plate 17. As shown in Figs. 6, 7, 8 and 10, the upper part of the member 123 is in the form of a channel which defines a relatively long U in cross-section. Beginning with a point indicated 124 in Figs. 9 and 10, the lower part of this member has an L-shape, as more clearly shown in Figs. 12 and 13. The upper part of the member 123 carries on its back surface a plate 125 (Figs. 4, 5 and 7) which is secured to the member 123 by means of rivets 126. This plate extends outwardly at the sides beyond the side edges of the member 123, and in these projecting portions are elongated vertically arranged slots 127. Shoulder screws 128 as shown on Figure 4 are passed through these slots and are received in threaded engagement in the plate 17. The heads of these screws are spaced slightly away from the plate 125 so that the plate has free sliding movement on the plate 17.

At the bottom, the member 123 is secured to the plates 17 and 26 for sliding movement by means of a headed bolt 129, as shown in Figs. 9, 10 and 12. As shown in Figs. 10 and 12, the member 123 at the bottom carries a block-like plate 130 and also an elongated vertically po-

sitioned plate 131 placed in front of the plate 130 as shown in Fig. 10. A cover plate 132 is positioned on the plate 131. The plates 130, 131 and 132 are secured together and also to the member 123 by means of screws 133 (Fig. 9). The plate 130 has an elongated opening 130a which fits about a reduced part 134 which is free to rotate on the bolt 129, while the plate 131 has an elongated opening 135 in which the head of the bolt 129 slides. It will be observed that by reason of this arrangement the plates 130, 131, 132, as well as the member 123, are secured to the walls 17 and 26 for sliding motion relative to them. A spacer plate 136 is placed between the back surface of the member 123 and the front surface of the plate 17.

A fixed pocket-like casing member 137 is placed around the lower ends of the assembly including the plates 130, 131 and 132 and the member 123, and is secured to the plate 17 in any suitable manner as by means of screws 138 (Fig. 12).

Also secured to the front face of the plate 131 above the plate 132 and having its lower end abutting the plate 132 is a sheet-like facing member 139. This may be secured to the plate 131 in any suitable manner, as by welding. Secured to the front surface of this facing member 139 at the top is a plate 140. This plate may be secured to the plates 131 and 139 in any suitable manner as by welding.

A crank arm 141 is pivotally connected at one end to the crank pin 122 and at its other end to a pin 142 which is secured to the plates 131 and 139 and also to the member 123 so that when the shaft 119 is rotated the entire assembly including the member 123 is reciprocated up and down.

The upper end of the plate 140 is spaced from the plate 143 which is positioned between the flanges of the member 123, as clearly shown in Fig. 10. The plate 143 is secured between these flanges by means of rivets 144. The plate 143 has a downwardly extending thinner section 143a, as shown, and between this section and the plate 140 is mounted a spur gear 145 and a ratchet wheel 146 which are secured together by means of pins, as shown in Fig. 10, and which are mounted to rotate upon a shaft 147 mounted on the plate 140. A pawl 148 is arranged to cooperate with the ratchet wheel 146. This pawl is rotatably mounted on a pawl arm 149 which is pivotally mounted on a bearing member 150 that is mounted in the plates 140 and 143, as clearly shown in Fig. 10. A spring-pressed plunger 151 normally holds the pawl 148 from rotating.

Carried by the upper end of the member 123 is a second gear wheel 152. This gear wheel is mounted in a plate 153 which is received between the flanges of the upper portion of the member 123 and which is slidably-mounted therein for relative vertical adjustment with reference to it. This plate 153 is provided with an elongated slot 154 which receives a key 155 which is secured between the flanges of the member 123 by the rivets 126 which are utilized to secure the plate 125 to the member 123. The plate 153 at its lower end is in contact with an adjusting screw 156 which is threaded in a block 157 which is secured between the flanges of the member 123 by means of rivets 158. The screw is provided with a head 159 whereby it may be adjusted and hence whereby the position of the 75

plate 153 may be adjusted, and also is provided with a lock nut 160.

Meshing with the two gear wheels 145 and 152 is a continuous chain 161, the tension of which is 5 adjusted by the screw 156. This chain is anchored to the bridge 49 and hence to the centering tube 48 by means of an anchor 162 secured to ends of the chain and which is received in a key-way 163 provided for it in a member 164. The member 164 is rigidly secured to a plate 165 which is riveted to the carriage 49, as clearly shown in Figs. 4 and 6.

It will be observed in view of the foregoing construction that if the shaft 119 be rotated, the 15 member 123 will be reciprocated up and down with a simple harmonic motion. And if the pawl 148 be out of engagement with its ratchet wheel 146, thereby permitting the spur gears 145 and 152 to 20 rotate freely, the member 123 will be reciprocated independently of the centering tube 48, which will remain stationary. If, however, the pawl be moved into engagement with its ratchet wheel, the 25 gears 145 and 152 will be locked against rotation, and hence the bridge 49 and centering tube 48 will be reciprocated with the member 123. The 30 pawl is biased by the weight of the pawl lever 149 to move into engagement with the ratchet wheel, but is restrained by means of a cylindrical member 166 mounted on the upper end of the latch member 107, and which is positioned to engage an 35 extension of the member 149, as shown in Fig. 9, to prevent engagement of the pawl until the latch is moved counter-clockwise, as viewed in this figure, to release the insulating material feed control lever 98 to permit insulating material to flow from its hopper. This movement of the latch, as pointed out previously, is controlled by the member 114, and the pawl will be free to move into engagement with the ratchet until the member 40 114 is operated to return the latch 107 to its latching position.

Suitable means are provided for applying to the sheath a plurality of intermittent impacting blows to settle the insulating material as it is 45 fed to the sheath. For this purpose, a vibrator 167 (Figs. 1 and 2) is provided. The vibrator 167 comprises a straight plunger hammer 169 arranged to tap the sheath 11, as shown in Fig. 1. The plunger hammer is rapidly reciprocated or 50 vibrated and engages the side of the sheath with intermittent impacting blows. The plunger hammer 169 is driven by means of any suitable vibrating mechanism 170. The vibrating mechanism has not been illustrated in detail for any suitable 55 vibrating mechanism may be used, and the details of this mechanism form no part of the present invention. The vibrator 167 is mounted upon a suitable bracket 171 which in turn is secured to the bracket 23. The vibrator is controlled by means 60 of a switch 172 mounted on the control lever 114, and which preferably will be of the fluid type, such as a suitable mercury switch. The contacts in this switch are so arranged that when the control lever 114 is in its position of Fig. 1, the vibrator will be deenergized, whereas when the arm is depressed to its position of Fig. 3, the mercury will complete a circuit through the switch 172 to 65 energize the vibrator.

In making an electric heating unit using the 70 apparatus of this invention, it will be understood that the terminals 12 will be secured to the resistance conductor 10 in the manner previously described, and then the sheath 11 will be slid up over the centralizer rod 48 until the jaws 35a of terminal hook 35 are exposed. The relatively

small head of the upper terminal 12 will then be inserted in the hook 35 on the lower end of rod 34.

Then the eyelet 44b will be pulled down so as to move the lever 38 from its position of Fig. 3 to its position of Figs. 1 and 4 in which position it is held by the latch 43. This operation elevates the rod 37 and thereby elevates the rod 34 and the upper terminal 12, so as to pull the hook 35 up into the centralizer 45, thus preventing accidental unlocking of the terminal from the hook while the necessary operations required of handling the sheath 11 for the loading operation of insulating powder 13 are being made.

The sheath 11 then will be slid down over the heating element 10 and the lower terminal 12, which is provided with the washer or head 31, will be received within the recess 32 previously referred to so as to close the lower end of the sheath 11 and also so as to anchor and center the lower terminal 12 with reference to the sheath. The lower end of the sheath will then be placed upon the base 29 so that the protuberance 30 on the base is received in the recess 32. Then the jaws 69 with inserts 78 will be closed about the upper end of the sheath to hold the sheath in its proper position in the apparatus. The over-center springs 80 function to hold the jaws closed.

Then by means of the knob 58 the carriage 52 and all of the parts connected with it will be lowered from its position of Figs. 1 and 2 to its position of Fig. 3. This lowers the centralizing tube 48 down into the sheath to its dotted line position shown in Fig. 19. Preferably, a stop 173 will be fixed on one of the rods 15, as shown in Figs. 1, 2 and 3, which will be engaged by the lower edge of carriage 52 to limit the lower travel of the carriage and hence of the centralizing tube. The stop will be positioned so that when it is engaged by the carriage 52, the centralizer 45 will have a small clearance from the head or washer 31. When the carriage is depressed it carries with it the roller 68a which engages the latch 43 in the manner previously described to release the lever 38 and permit it to move to its initial position where it is again engaged by the latch as shown in Fig. 3. This permits the rod 34 and terminal 12 to move back to their proper lower positions.

Then the lever 114 will be depressed from its position of Figs. 1 and 9 to its position of Fig. 3. This operation will start the vibrator 167. It will be understood that simultaneously with this operation of the lever 114 the power means driving the shaft 119 may be started by any suitable switch (not shown), or that this power means may have been started previously. The latter is preferred, and preferably the power means will operate the shaft 119 continuously during successive loading operations. Also when the lever 114 is depressed it will actuate the latch 107 to release the insulating material feed lever 98, which thereupon will move in the counterclockwise direction, as viewed in the figures, to elevate the feed gate 97 to permit the insulating material to flow from the hopper 93 into the upper end of the sheath 11. Also this operation of the latch will release the pawl-carrying member 149 to permit the pawl 148 to engage its ratchet wheel 146.

When the pawl 148 engages its ratchet wheel 146, the centralizer tube 48 will be oscillated up and down with the member 123, which member, as previously described, is reciprocated with a simple harmonic motion. Therefore, the centralizing tube as it is operated up and down will intermittently carry the centralizer 45 into engagement with the insulating material, the level of

which is continuously rising in the sheath. The centralizer will engage the insulating material on each stroke providing the level has risen high enough to permit the centralizer to contact it. When the centralizer engages the level of the insulating material, its downward movement is resisted and it is temporarily released from the reciprocating member 123 by the slippage between the ratchet wheel 146 and the pawl 148.

The centralizer exerts some pressure on the insulating material each time it engages it, because the total weight of the carriage and its elements plus its momentum and also the pawl 148 resists somewhat the slippage it has with the ratchet 146 due to the weight of the pawl lever 149. This pressure displaces the insulating material both inside and outside the centralizer causing the displaced material to move upwardly. The upward movement of the insulating material inside the centralizer is facilitated by the inclined surface 47a. On each of the downward strokes of the centralizer, the insulating material climbs up the inclined surface to the desired level. This upward movement of the insulating material on the inside of the tube elevates slightly the turns of the resistance conductor. The force with which the centralizer tube thus displaces the insulating material and the inclination of the surface 47a are so controlled that the insulating material elevates the turns just enough to compensate for the sag of the turns due to their own weight and the weight of the settling material. This is particularly important due to the present trend of using heating elements of a large number of turns of light gauged wire and relatively large outside diameters, as this is a condition which causes excessive sag.

Due to the fact that the centralizer intermittently engages the level of the insulating material within the sheath and is temporarily released in the manner described, the centralizing tube will be gradually elevated as the level of the insulating material rises, and as it is thus elevated, it will carry with it the bridge 49 and the carriage 52. As these members rise, the cam 118 carried by the bridge 52 rises and eventually its inclined surface 118b will engage the roller 118a on the powder feed lever 98 so as to rotate it in a clockwise direction to depress the gate 97 to cut down the flow of insulating material to the sheath. The flow will be materially reduced by this operation and this reduction in the rate of flow is caused as the insulating level reaches approximately the lower end of the upper terminal 12. The apparatus continues to function with the insulating material flowing in at the reduced rate until the sheath is loaded at which time the inclined surface 118c of the cam 118 engages the roller 118a and causes the lever 98 to rotate to its original position to completely shut off the flow of powder to the sheath.

At this time, the wedge 59 will be engaged by the rollers 62 so that the wedge and the parts attached to it will be secured in their upper positions; it is to be understood that during the upward travel of the centering tube, the plate 60 will rest upon the bridge 49 and that after the wedge 59 has been engaged and held by the levers 63, the bridge 49 and its associated parts will drop downwardly from the plate 60 the limited distance permitted by the bolts 61. This operation causes the centralizer to drop down to its dotted line position of Fig. 19 so that it will hold the upper terminal 12 from migrating off center due to transmitted vibrations. This opera-

tion also permits the cam 118 to drop away from the roller 118a. However, previous to this dropping away of the cam 118, the operating lever 114 will have been engaged by the pin 174 on the carriage 52 so as to have been operated from its position of Fig. 3 to its initial position of Fig. 1. This operation of the lever 114 will have returned the latch arm 107 to its initial position to hold the lever 98 in its initial position regardless of the fact that the cam 118 has been withdrawn somewhat from the roller 118a. The latch 107a is free to buckle to prevent possible damage due to a premature operation of the latch to its latching position.

Also, when the lever 114 returns to its initial position to move the latch arm 107 to its initial position, the roller 166 carried by the latch will engage the pawl-carrying member 149 so as to release the pawl 148 from the ratchet 146. Also the lever 114 will operate the switch 172 to de-energize the vibrator 170.

It is to be noted that the roller 68a will not have any effect on the latch 43 when the centralizer tube rises because at this time the latch will be in its position of Fig. 3 and the cam 43a will be removed from the path of the roller.

It will be understood that as the centralizing tube rises in the sheath during the filling operation the ribs 46 on the centralizer will slidably engage the inner walls of the sheath so as to hold the resistance coil 10 centrally within the sheath. Also, it will be understood that the insulating material can flow through the centralizer to the portions of the sheath under it through the spaces between the centralizer and the sheath and also down through the resistance coil.

Moreover, it will be understood that as the powder level rises during the loading operation and as it is acted on by the oscillating centralizer, the vibrator 167 is continuously functioning to settle the insulating material in the sheath as it is admitted to the sheath.

When the sheath has been loaded, to remove it from the machine the jaws are moved to their open positions. They are positively opened by means of their springs 81 and their open positions are limited by the stop plate 91, as previously described. Then, the entire heating unit may be elevated from its support 29 to remove the head 33 of the upper terminal from the hook 35 and to withdraw the lower end of the sheath from the protuberance 30 on the support 29.

The apparatus is then in its initial condition ready for loading another heating unit.

If at any time it is desired to stop the operation of the machine before the sheath has been filled it is merely necessary to return the operating lever 114 to its position of Fig. 1. Here also, the latch 107a can buckle so as to permit the control arm to move to this position even though the lever 98 is in its feed gate open position. Also the powder flow can be stopped by rotating the power feed lever 98 clockwise.

Also it is to be noted that the spring-pressed plunger 151 engaging the pawl 148 is provided to permit slippage of the pawl in case of emergency. For example, this emergency may occur due to the centralizer vanes 46 getting stuck in the sheath 11 due to either insufficient clearance or particles getting wedged between these two elements.

Different lengths of sheaths within small limits may be filled with this apparatus by providing a resilient mounting for the head 29 which supports the sheath. This may be done by mounting

the head 29 on a plunger 29a which is received in the base 28 and which will be arranged in the form of a cylinder. Positioned within the cylinder and below the plunger 29a is a suitable compression spring 29b.

It will be understood that a single machine may be operated as has just been described to load the sheaths, or that a number of these machines may be arranged in a bank or battery, or 10 arranged on a rotary platform so that the operator can work from a fixed position.

Important features of this invention are the provision of the means for positively driving the centralizing tube with a simple harmonic motion 15 so that it intermittently engages the level or surface of the insulating material as it rises in the sheath. As previously pointed out, each time that the centralizer engages the insulating material it displaces the insulating material upwardly to 20 eliminate sag of the conductor turns.

Another important feature of this invention is the insurance of uniform density of insulating material throughout the sheath. The reduction in the rate of feed of the insulating material at 25 the upper end of the sheath insures a more dense settling of the insulating material than would be the case if it flowed in at the same rate as in the lower portions of the sheath. This insulating material flowing in at a slower rate is vibrated for a sufficiently long period of time to insure the 30 same density at the top of the sheath as at the bottom.

Furthermore, the slowing down of the feed at the top is of importance in that it is possible to 35 control the height to which the insulating material rises in the sheath and also permits the vibrator to pack the powder at the top to a greater density than is the case without the powder flow slowing down. This height is accurately controlled as one of the functions of the machine and the flow of insulating material is instantaneously shut off at the predetermined level.

The constant vibratory hammering of the sheath by the vibrator and the controlled rise of 40 the oscillating centralizing tube not only control the uniformity of the spacing of the turns of the winding but also insure a uniform density in the insulating material.

While I have shown a particular embodiment 50 of my invention, it will be understood, of course, that I do not wish to be limited thereto since many modifications may be made, and I, therefore, contemplate by the appended claims to cover any such modifications as fall within the true 55 spirit and scope of my invention.

What I claim as new and desire to secure by Letters Patent of the United States is:

1. Apparatus for loading granular insulating material into the sheath of a sheath-wire heating unit that is provided with a sheath, and a coiled resistance conductor in said sheath which is embedded in and held in spaced relation with said sheath by said insulating material, comprising 60 means for holding said sheath in an upright position, means for feeding said insulating material into the upper end of said sheath, a guide member slidably mounted in said sheath around said resistance conductor constructed and arranged to hold it from substantial lateral movement in said 65 sheath, reciprocating driving means for said guide member for reciprocating it in said sheath as the sheath is being filled with said insulating material, said driving means being constructed and arranged to cease driving said guide member 70 temporarily when the motion of said guide mem-

ber is stopped by its engagement with said insulating material, and for automatically redriving it on its stroke to move said guide member away from said material so that said guide member forcibly and periodically engages said insulating material as it fills said sheath and progressively moves in said sheath toward said upper end as the amount of insulating material in said sheath increases, said guide member being provided at its lower end with a portion adjacent said conductor inclined upwardly and inwardly toward said conductor so that when it forcibly engages said insulating material it elevates the insulating material sufficiently to prevent the turns of said conductor from moving toward the lower end of said sheath due to their own weight and the weight of the insulating material fed in.

2. Apparatus for loading insulating material into the sheath of a sheathed heater having a helical resistance conductor in said sheath embedded in said insulating material, comprising means for holding said sheath in an upright position, means for continuously feeding said insulating material into the upper end of said sheath at a regulated rate, a guide member slidably mounted in said sheath around said conductor to hold said conductor from moving laterally in said sheath, a reciprocating driving member for said guide member, a ratchet wheel on said driving member, a yielding pawl on said driving member engaging said ratchet wheel with predetermined yielding force, and connection means between said ratchet wheel and said guide member for reciprocating said guide member when said pawl prevents said ratchet wheel from rotating, and said pawl yielding so that said ratchet wheel will rotate temporarily each time said guide member forcibly engages the insulating material in said sheath so that said driving member continues its movement to the end of its stroke independently of said guide member, whereby as the amount of material fed in the sheath increases said guide member is gradually and progressively moved upwardly in said sheath.

3. Apparatus for loading granular insulating material into a sheathed heater of the type having an outer sheath and a helical resistance conductor in said sheath embedded in the granular resistance material, comprising means for holding said sheath in an upright position, means for feeding said granular insulating material into the upper end of said sheath at a regulated rate, a guide member slidably mounted in said sheath around said conductor to hold said conductor from moving laterally in said sheath, a driving member for said guide member, means mounting said driving member for vertical reciprocating motion, a pair of vertically-spaced rotatable members mounted for free motion on said driving member, a belt mounted on said rotatable members, means attaching said belt to said guide member, and means for connecting said belt to said driving member so that guide member is elevated and depressed in said sheath by said driving member as it reciprocates, said connecting means being constructed and arranged to temporarily release said belt from said guide member on the downward stroke of said driving member upon the exertion of predetermined resistance to the downward motion of said guide member by said insulating material.

4. Apparatus for loading granular insulating material into the sheath of a sheathed heater having a helical resistance conductor in said sheath embedded in the granular resistance ma-

5 terial, comprising means for holding said sheath in an upright position, means for feeding said granular insulating material into the upper end of said sheath at a regulated rate, a guide member slidably mounted in said sheath around said conductor to hold said conductor from moving laterally in said sheath, a driving member for said guide member, means mounting said driving member for vertical reciprocating motion, a pair of vertically-spaced gears on said driving member mounted for free rotation on fixed axes, an endless chain mounted on said gears intermeshed with the teeth thereon, means attaching said chain to said guide member, a ratchet wheel attached to one of said gears so as to rotate with it, and a pawl carried by said driving member arranged to engage said ratchet wheel to prevent rotation thereof except when the motion of said guide member downwardly in said sheath is resisted by its engagement with said insulating material.

20 6. Apparatus for loading granular insulating material into the sheath of a sheath wire heating unit provided with a resistance conductor in said sheath embedded in and supported in spaced relation to said sheath by said insulating material, comprising a vertical frame, means for supporting the sheath in an upright position in said frame, means for continuously delivering said insulating material into the upper end of said sheath, a carriage mounted on said frame for vertical movement therein, a guide attached to said carriage so as to move with it and constructed and arranged to be mounted in and moved vertically in said sheath to prevent substantially lateral movement of said resistance conductor in said sheath while said insulating material is being fed in, a driving member mounted in said frame for vertical reciprocating motion, means for continuously reciprocating said driving member, and a driving connection between said driving member and carriage for reciprocating said carriage and thereby reciprocating said guide up and down in said sheath including means for temporarily releasing said carriage from said driving member when said insulating material resists the downward motion of said guide so that said driving member can continue its downward stroke independently of said guide.

25 7. Apparatus for loading granular insulating material into the sheath of a sheath wire heating unit provided with a resistance conductor in said sheath embedded in and supported in spaced relation to the sheath by said insulating material, comprising means for holding said sheath in an upright position, means for continuously feeding said insulating material into the upper end of said sheath, a guide for said resistance conductor slidably mounted in said sheath and constructed and arranged to hold said conductor from substantial lateral movement in said sheath while said insulating material is being loaded, a reciprocating driving member having a fixed operating stroke, a driving connection between said driving member and said guide constructed and arranged to forcibly drive said guide up and down in said sheath and to release said guide temporarily upon a predetermined resistance to its downward movement by its engagement with said insulating material so that said driving member may complete its downward stroke independently of said guide, the driving connection being reestablished on the next upward stroke of said driving member so that said guide is reciprocated up and down in said sheath and is

gradually elevated therein as said insulating material is fed in, and means releasing said driving connection when said guide has been elevated a predetermined distance.

7. Apparatus for loading granular insulating material into the sheath of a sheath wire heating unit provided with a resistance conductor in said sheath embedded in and supported in spaced relation to the sheath by said insulating material, comprising means for holding said sheath in an upright position, means for continuously feeding said insulating material into the upper end of said sheath, a guide for said resistance conductor slidably mounted in said sheath and constructed and arranged to hold said conductor from substantial lateral movement in said sheath, a reciprocating driving member having a fixed operating stroke, a driving connection between said driving member and said guide constructed and arranged to forcibly drive said guide up and down in said sheath and to release said guide temporarily upon a predetermined resistance to its downward movement by the engagement of said guide with said insulating material so that said driving member can complete its downward stroke independently of said guide, the driving connection being reestablished on the next upward stroke of said driving member so that said guide is reciprocated up and down in said sheath and is gradually elevated therein as the level of said insulating material rises, and means for releasing said driving connection and for stopping the flow of insulating material to said sheath when said guide has been elevated a predetermined distance.

8. Apparatus for loading granular insulating material into the sheath of a sheathed heater having a helical resistance conductor in said sheath embedded in the granular resistance material, comprising means for holding said sheath in an upright position, means for feeding said granular insulating material into the upper end of said sheath at a regulated rate, a guide slidably mounted in said sheath around said conductor to hold said conductor from substantial lateral movement in said sheath, a reciprocating driving member for said guide, a driving connection between said driving member and said guide for moving said guide up and down in said sheath including a ratchet wheel mounted on said driving member, a pawl mounted on said driving member for engaging said ratchet wheel to prevent its rotation, means connecting said ratchet wheel with said guide so that when the wheel is locked against rotation said guide is driven by said driving member and when it is released said driving member operates independently of said guide, the pawl automatically releasing said ratchet wheel upon the occurrence of a force of predetermined magnitude resisting the downward motion of said guide so that said guide is progressively elevated as the level of insulating material rises in said sheath, a lever controlling the movement of said pawl into and out of engagement with said ratchet wheel, means automatically operating said lever to move said pawl out of engagement with said ratchet wheel when said guide has been elevated a predetermined distance, and means operated by said lever for cutting off the flow of insulating material to said sheath when said lever moves said pawl out of engagement with said ratchet wheel.

9. Apparatus for loading granular insulating material into the sheath of a sheath wire heating unit provided with a resistance conductor in said sheath embedded in and supported in spaced re-

lation with the sheath by said insulating material, comprising means for supporting said sheath in an upright position, a grasping member for grasping and holding the upper end of said conductor, a tubular guide member slidably mounted in said sheath to hold said resistance element in spaced relation to said sheath, and when moved down into said sheath surrounding said grasping member, said guide member being movable upwardly to a position to expose said grasping member when said grasping member is in its position for attachment with said upper end of said resistance conductor, means for elevating said grasping member up into said guide member, and means operated responsively to the movement of said guide member down into said sheath for returning said grasping member to said position.

10. Apparatus for loading granular insulating material into the sheath of a sheath wire heating unit provided with a resistance conductor in said sheath and embedded in and supported in spaced relation with the sheath by said compacted insulating material, the resistance conductor being connected at its ends to terminals mounted in the ends of said sheath, comprising means for supporting said sheath in an upright position, a grasping member for grasping and holding one of said terminals, a tubular centering device mounted for movement in said sheath to hold said resistance element centrally of said sheath, and when moved down into said sheath surrounding said grasping member, said centering device being movable upwardly to a position to expose said grasping member when said grasping member is in its position for attachment with said one terminal, a member attached to said grasping member for moving it from said position up into said centering member after said terminal has been attached, means biasing said grasping member toward said position, a latch for holding it up in said centering device, and a cam attached to said centering device for operating said latch to release said grasping member when the centering device is lowered into said sheath to thereby permit it to return to said position.

11. Apparatus for loading granular insulating material into the sheath of a sheath wire heating unit provided with a resistance conductor in said sheath embedded in and supported by said insulating material, comprising means for holding said sheath in an upright position, feeding means for delivering said insulating material into the upper end of said sheath so as to fill the sheath from the bottom to the top, a movably mounted control member, means operated by said control member when the latter is moved to a first position for controlling said feeding means to reduce the rate of feed of said insulating material into said sheath and when moved to a second position for controlling said feeding means to shut off the feed of said insulating material to said sheath, and means engaging the surface of the insulating material in said sheath for operating said control member to said first position when said insulating material attains a predetermined height in said sheath, and to said second position when said insulating material reaches substantially the upper end of said sheath.

12. Apparatus for loading granular insulating material into the sheath of a sheath wire heating unit provided with a resistance conductor in said sheath embedded in and supported in spaced relation to the sheath by said insulating material, comprising means for holding said sheath in an

upright position, a delivery member for directing said insulating material into the upper end of said sheath, a gate controlling the flow from said member to said sheath, a lever for operating said gate between opened and closed positions, means biasing said lever to open said gate, manually releasable means holding said lever in its position to close said gate against the force of said biasing means, a cam cooperating with said lever constructed and arranged when moved to a first position to operate said lever to partially close said gate thereby to cut down the rate of flow of said insulating material into said sheath and when moved to a second position to operate said lever to shut said gate to stop the flow of said insulating material to said sheath, and means operated by said insulating material as its level in said sheath rises for operating said cam to said first position when said level attains a predetermined height in said sheath and to said second position when said level rises substantially to the upper end of said sheath.

13. Apparatus for loading granular insulating material into the sheath of a sheath wire heating unit that is provided with a sheath, and a coiled resistance conductor in said sheath which is embedded in and held in spaced relation with said sheath by said insulating material, comprising means for holding said sheath in an upright position, means for feeding said insulating material into the upper end of said sheath, a guide member slidably mounted in said sheath provided with a section around said resistance conductor so as to hold it from substantial lateral movement in said sheath while the sheath is being filled, means for effecting up and down movements of said guide member in said sheath so that the lower end of said section periodically engages said insulating material as it fills said sheath, said lower end being provided with a tapered wall inclined upwardly and inwardly toward said conductor so that when it engages said insulating material it elevates the insulating material about said turns sufficiently to prevent said turns from moving toward the lower end of said sheath due to their own weight and the weight of the insulating material fed in.

14. Apparatus for loading sheath wire heating units provided with a sheath, a resistance conductor in said sheath and granulated insulating material within said sheath embedding said resistance conductor to hold it in spaced relation with said sheath, comprising a support for the lower end of said sheath upon which said sheath can be placed in an upright position, and a plurality of jaws arranged to clamp the upper end of said sheath, said jaws being provided with sections defining sheath abutments over the upper end of said sheath when the jaws are closed, and also having sections above the sheath which when the jaws are closed define a passageway for guiding the insulating material to the upper end of said sheath.

15. Apparatus for loading granular insulating material into the sheath of a sheath wire heating unit provided with a resistance conductor in said sheath embedded in and supported in spaced relation with the sheath by said insulating material, comprising a support for the lower end of said sheath upon which said sheath can be placed in an upright position, a plurality of jaws arranged to clamp the upper end of said sheath, means pivotally mounting said jaws for movement to closed positions to clamp said sheath and to open positions to release said sheath, a driving connec-

tion between said jaws, and over-center spring means connected with said jaws to move them positively to their closed and opened positions.

16. Apparatus for loading sheath wire heating units provided with a sheath, a resistance conductor in said sheath and granulated insulating material within said sheath embedding said resistance conductor to hold it in spaced relation with said sheath, comprising a frame, means for holding said sheath in an upright position in said frame, feeding means for delivering said insulating material to the upper end of said sheath, a centralizing tube slidably mounted in said sheath to centralize said resistance conductor, a carriage slidably mounted in said frame for vertical movement therein, means securing said tube to said carriage, a plate mounted in said frame for vertical movement therein, means for reciprocating said plate through a fixed stroke, connection means between said plate and said carriage for positively elevating said carriage and centering tube when said plate moves up and for lowering said carriage and centering tube when said plate moves down and constructed and arranged to release said carriage temporarily when the downward movement of said centering tube is resisted by the insulating material in said sheath so that the plate can continue its downward movement to the lower end of its stroke and to reestablish the driving connection for movement by said plate when it returns to the upper limit of its stroke, whereby said tube is reciprocated in said sheath and the lower limit of its movement is progressively elevated in said sheath, a manually operable device for operating said connection means to connect said carriage with said plate, and for operating said feeding means to start the flow of insulating material to said sheath, means operated by said carriage as it is elevated for controlling said feeding means to shut off the flow of insulating material to said sheath, and means operated by said carriage for operating said connection means to disconnect said plate from said carriage.

17. Apparatus for loading sheath wire heating units provided with a sheath, a resistance conductor in said sheath and granulated insulating material within said sheath embedding said resistance conductor to hold it in spaced relation with said sheath, comprising a frame, means for holding said sheath in an upright position in said frame, feeding means for delivering said insulating material to the upper end of said sheath, a centralizing tube slidably mounted in said sheath to centralize said resistance conductor, a carriage slidably mounted in said frame for vertical movement therein, means securing said tube to said carriage, a plate mounted in said frame for vertical movement therein, means for reciprocating said plate through a fixed stroke, connection means between said plate and said carriage for positively elevating said carriage and centering tube when said plate moves up and for lowering said carriage and centering tube when said plate moves down and constructed and arranged to release said carriage temporarily when the downward movement of said centering tube is resisted by the insulating material in said sheath so that the plate can continue its downward movement to the lower end of its stroke and to reestablish the driving connection for movement by said plate when it returns to the upper limit of its stroke, whereby said tube is reciprocated in said sheath and the lower limit of its movement is progressively elevated in said sheath, a manually oper-

able device for operating said connection means to connect said carriage with said plate, and for operating said feeding means to start the flow of insulating material to said sheath, means operated by said carriage as it is elevated for controlling said feeding means to cut down the rate of flow of said insulating material to said sheath when the level of insulating material in said sheath reaches a predetermined height and for shutting off the flow completely when said sheath is filled, and means operated by said carriage for operating said connection means to disconnect said plate from said carriage.

18. Apparatus for loading sheath wire heating units provided with a sheath, a resistance conductor in said sheath and granulated insulating material within said sheath embedding said resistance conductor to hold it in spaced relation with said sheath, comprising a frame, means for holding said sheath in an upright position in said frame, feeding means for delivering said insulating material to the upper end of said sheath, a centralizing tube slidably mounted in said sheath to centralize said resistance conductor, a carriage slidably mounted in said frame for vertical movement therein, means securing said tube to said carriage, a plate mounted in said frame for vertical movement therein, means for reciprocating said plate through a fixed stroke, connection means between said plate and said carriage for positively elevating said carriage and centering tube when said plate moves up and for lowering said carriage and centering tube when said plate moves down and constructed and arranged to release said carriage temporarily when the downward movement of said centering tube is resisted by the insulating material in said sheath so that the plate can continue its downward movement to the lower end of its stroke and to reestablish the driving connection for movement by said plate when it returns to the upper limit of its stroke, whereby said tube is reciprocated in said sheath and the lower limit of its movement is progressively elevated in said sheath, a manually operable device for operating said connection means to connect said carriage with said plate, and for operating said feeding means to start the flow of insulating material to said sheath, means operated by said carriage as it is elevated for controlling said feeding means to shut off the flow of insulating material to said sheath, means operated by said carriage for operating said connection means to disconnect said plate from said carriage, and yieldable means for holding said carriage in its upper position, said means being manually releasable to permit said carriage to be lowered.

19. Apparatus for loading sheath wire heating units provided with a sheath, a coiled resistance conductor in said sheath and granulated insulating material within said sheath embedding said resistance conductor to hold it in spaced relation with said sheath, comprising means for supporting said sheath in an upright position, means for feeding said insulating material into the upper end of said sheath, a tubular guide member slidably mounted in said sheath and constructed and arranged to hold said resistance conductor in fixed spaced relation with said sheath, and reciprocating driving means for said guide member for reciprocating it in said sheath as the sheath

is being filled with said insulating material, said driving means being constructed and arranged to release said guide member temporarily when the motion of said guide member is stopped by the engagement of its lower end with said insulating material and the pressure of said guide member on said insulating material exceeds a predetermined value, and for automatically reengaging it on its stroke to move said guide member away from said material so that the guide member forcibly and periodically engages the insulating material as it fills said sheath, and the lower end of the inner wall portion of said guide member being inclined upwardly and inwardly toward said conductor, the pressure exerted on said insulating material when said guide member forcibly engages it forcing said material up said inclined surface to prevent the turns of said conductor from sagging downwardly in said sheath.

20. Apparatus for loading granular insulating material into the sheath of a sheath wire heating unit that is provided with a sheath, and a coiled resistance conductor in said sheath which is embedded in and held in spaced relation with said sheath by said insulating material, comprising means for holding said sheath in an upright position, means for feeding said insulating material into the upper end of said sheath, a guide member slidably mounted in said sheath provided with a tubular section surrounding said resistance conductor so as to hold it from substantial lateral movement in said sheath while the sheath is being filled, means for effecting up and down movements of said guide member in said sheath so that the lower end of said section forcibly and periodically engages said insulating material as it fills said sheath, said lower end being provided with a substantially flat wall and a second wall inclined upwardly and inwardly therefrom toward said conductor, said walls when forced into contact with said insulating material elevating said insulating material around the turns of said conductor sufficiently to prevent the turns from moving toward the lower end of said sheath due to their own weight and the weight of the insulating material fed in.

21. Apparatus for loading granular insulating material into the sheath of a sheath wire heating unit that is provided with a sheath, and a coiled resistance conductor in said sheath which is embedded in and held in spaced relation with said sheath by said insulating material, comprising means for holding said sheath in an upright position, means for feeding said insulating material into the upper end of said sheath, a guide member slidably mounted in said sheath provided with a section around said resistance conductor so as to hold it from substantial lateral movement in said sheath while said sheath is being filled, means for effecting up and down movements of said guide member in said sheath so that the lower end of said section periodically engages said insulating material as it fills said sheath, said lower end being provided with walls positioned at an angle to each other so that when they engage said insulating material they elevate the material about said turns sufficiently to prevent said turns from moving toward the lower end of said sheath due to their own weight and the weight of the insulating material fed in.

JOHN LEWIS ANDREWS.
